Patented July 29, 1975

236,074

COMBINED BOTTLE SCRAPER AND CAP

William P. Monagle, 507 Pueblo St.,
Boise, Idaho 83702

Filed Feb. 28, 1974, Ser. No. 446,866

Term of patent 14 years

Int. Cl. D7—05

U.S. Cl. D7—184

FIG. 1 is a left front perspective view of the combined bottle scraper and cap embodying my new design.

FIG. 2 is a right rear perspective view of the combined bottle scraper and cap.

I claim:

The ornamental design for a combined bottle scraper and cap, substantially as shown.
